UNITED STATES PATENT OFFICE.

HAROLD W. MUNRO, OF PROVIDENCE, RHODE ISLAND.

DESIGN FOR AN IMAGE.

Application filed September 12, 1924. Serial No. 10,764. Term of patent 14 years.

To all whom it may concern:

Be it known that I, HAROLD W. MUNRO, a citizen of the United States of America, residing at Providence, county of Providence, State of Rhode Island, have invented a new, original, and ornamental Design for an Image, of which the following is a specification, reference being had to the accompanying drawing, forming a part thereof.

I claim:

The ornamental design for an image, as shown.

HAROLD W. MUNRO.
